LIQUID FILTER FOR AQUARIA

Richard D. Scattergood, Philadelphia, Pa.

Application August 24, 1953, Serial No. 26,563

Term of patent 14 years

(Cl. D91—2)

Fig. 1

Fig. 2

Fig. 3

To all whom it may concern:

Be it known that I, Richard D. Scattergood, a citizen of the United States, residing in Philadelphia, county of Philadelphia, State of Pennsylvania, have invented a new, original, and ornamental Design for a Liquid Filter for Aquaria, of which the following is a specification, reference being had to the accompanying drawing, which forms a part thereof.

Figure 1 is a front perspective view of a liquid filter for aquaria as shown in my new design;

Figure 2 is a rear perspective view of the same; and Figure 3 is a top plan view thereof.

I claim:

The ornamental design for a liquid filter for aquaria, as shown.
